CLAIM

The ornamental design for backpack, as shown and described.

DESCRIPTION

FIG. 1 is a front perspective view of a backpack.

FIG. 2 is a front side elevation view thereof.

FIG. 3 is a back side elevation view thereof.

FIG. 4 is a left side elevation view thereof.

FIG. 5 is a right side elevation view thereof.

FIG. 6 is a top view thereof; and,

FIG. 7 is a bottom view thereof.

The features shown in broken lines in the drawing depict environmental subject matter only and form no part of the claimed design.
